UNITED STATES PATENT OFFICE.

FRED W. TOBEY, OF GRAND RAPIDS, MICHIGAN.

TYPE-WRITER CABINET.

No. 848,783.

Specification of Letters Patent.

Patented April 2, 1907.

Application filed September 11, 1905. Serial No. 277,893.

To all whom it may concern:

Be it known that I, FRED W. TOBEY, a citizen of the United States, residing at Grand Rapids, in the county of Kent and 5 State of Michigan, have invented certain new and useful Improvements in Type-Writer Cabinets; and I do hereby declare the following to be a full, clear, and exact description of the invention, such as will enable 10 others skilled in the art to which it appertains to make and use the same.

My invention relates to improvements in type-writer cabinets, and more particularly to such cabinets having an inner chamber in 15 which is a movable platform to support the type-writer, and above which chamber is a movable cover connected to the platform, whereby when as the cover is opened and closed the platform is raised and lowered; and 20 its object is to provide the device with improved means for connecting the platform and cover, to provide means for locking the cover and platform in open position, and to provide the device with various new and useful features hereinafter more fully described, 25 and particularly pointed out in the claims, reference being had to the accompanying drawings, in which—

Figure 1 is a vertical section of a device 30 embodying my invention, showing the same in closed position; Fig. 2, a perspective view of the same; and Fig. 3, a vertical section of the same, showing the device in open position in solid lines and in partially-opened portion 35 in broken lines.

Like numbers refer to like parts in all of the figures.

The case is in the usual form of a desk or table, as may be preferred, and having a 40 chamber in its interior to contain the type-writer and its supporting-table. This chamber is closed at the sides by the usual chests of drawers or other receptacles, and the bottom of the chamber is provided with a closure 45 7, preferably an open frame, and a concave front 6, which bottom and front are spaced apart from the sides of the chamber and supported at the front by a metal bracket 16 and at the rear by the back of the case to permit 50 the passage through said space of the various connecting-rods and levers to support and operate the platform for the type-writer.

In the preferred form shown the movable part of the top consists of two separate sections—a front section 1, hinged at the rear to 55 the intermediate section, as at 3, to which is

attached a downwardly-extended apron 5, forming a part of the front of the case when closed, and an intermediate section 2, hinged to the stationary part of the top at its rear, 6 as at 4.

8 is a movable platform on which the type-writer is supported. This platform is carried upon four parallel arms 9 and 10, pivoted at one end to the platform near its respective corners and at the other end to the sides of the chamber of the case and extending through the space between the bottom 7 and concave 6 and said sides of the chamber and adapted to turn to a vertical position 70 when the device is open for use and to turn rearward and downward together with the platform when the device is closed.

To operate and adjust the arms and platform, levers 11 are pivoted at one end to the 75 side walls of the case and connected at the other end by rods 12 to the arms 10, and from the levers 11 other connecting-rods 13 extend upward and are connected to short arms 14, rigidly attached to the section 2 of the top. 80 Near the rear of the platform 8 is an upwardly-projecting stop 15, adapted to engage the lower edge of the apron 5 when the device is open, and thus lock the device in open position until the front edge of the section 1 is 85 lifted to release the same. The hinge 3 being on the under side of the parts 1 and 2 forms a rule-joint between these parts, whereby when the front edge of the section 1 is lifted to open the device the sections 1 and 2 form a 90 lever turning on the pivot formed by the hinges 4, the arms 14 thus forming the other member of a bell-crank lever, whereby through the rods 13, levers 11, and rods 12 the arms 9 and 10 are turned from the rearwardly-inclined position to vertical position, and thus carry the platform 8 in a horizontal position upward and forward to position for using the type-writer, as shown in Fig. 3.

When the device is nearly open, the front part 1 can be turned downward and forward and the opening process completed by pushing the upper part of the section 2 backward to open position, as indicated in Fig. 3. When the front of the part 1 is lowered to 105 place and the apron 5 engaged by the stop 15, the device not only is locked in open position, but the entire section 1 is in horizontal and proper position to be used as an elevated table at the rear of the type-writer, and the apron 5 closes the space between the section 1 and the platform, thus completing the clo-

sure of the chamber below and preventing anything from falling into the same.

Having thus fully described my invention, what I claim, and desire to secure by Letters 5 Patent, is—

1. In a type-writer cabinet, a case, a platform, means for movably supporting the platform, a stop on the rear of the platform, a cover divided transversely into three parts 10 and hinged to fold upon itself in horizontal planes with the middle part inverted, and an apron on the front of the cover adapted to engage the stop to lock the device with the platform elevated and the cover open.
- 15 2. In a type-writer cabinet, a case having an inner chamber, a platform movable in the chamber, means for movably supporting the platform, a stop on the platform, a cover to the chamber and having a hinged rear portion 20 adapted to turn to reversed horizontal positions, and a front portion hinged thereto to move rearward without reversing, an apron on the cover to engage the stop, and means for connecting the rear portion of the cover 25 and said platform-supporting means to simultaneously adjust the cover and platform.
3. In a type-writer cabinet, a case having an inner chamber, a platform movable in the chamber, means for supporting and moving 30 the platform, a cover for the chamber divided

into front, middle, and rear parts, said parts being hinged to each other, the rear part being fixed, the middle part being adapted to turn to reversed horizontal positions, the front part being moved rearward thereby 35 without reversal, a bottom in the chamber having an upwardly-extended front portion, and an apron on the front portion of the cover adapted to engage the front of the bottom when the device is closed, and to engage 40 the rear of the platform when the device is open.

4. In a type-writer cabinet, the combination of a case having an inner chamber, a platform movable in the chamber, parallel 45 arms pivoted to the platform at one end and to the sides of the chamber at the other end, a cover having a hinged portion adapted to turn to reversed horizontal positions, a rigid arm on said portion, a toggle-joint lever pivoted 50 at its respective ends to one of the parallel arms and to the case, and a rod connecting the said lever and the arm on the cover.

In testimony whereof I affix my signature in presence of two witnesses.

FRED W. TOBEY.
